J. D. CARROLL.

PISTON VANE.

APPLICATION FILED JAN. 20, 1919.

1,354,281.

Patented Sept. 28, 1920.

UNITED STATES PATENT OFFICE.

JOHN D. CARROLL, OF WEST LAFAYETTE, INDIANA, ASSIGNOR TO TURBO ROTARY ENGINE COMPANY, OF EVANSVILLE, INDIANA, A CORPORATION OF INDIANA.

PISTON-VANE.

1,354,281.

Specification of Letters Patent. Patented Sept. 28, 1920.

Application filed January 20, 1919. Serial No. 272,021.

To all whom it may concern:

Be it known that I, JOHN D. CARROLL, a subject of the King of Great Britain, residing at West Lafayette, in the county of Tippecanoe and State of Indiana, have invented certain new and useful Improvements in Piston-Vanes, of which the following is a specification.

This invention relates to piston vanes or blades of the type employed in steam and gas engines of the rotary and oscillating expansion type. A difficulty hitherto experienced in engines of these types has been to secure a substantially steam-tight joint between the edges of the piston vane or blade and the walls of the cylinder or cylinder and piston drum with which the edges are in sliding contact. A further difficulty which has been experienced has grown out of the excessive wear on the edges of the piston vane, which soon results in leakage of the motive fluid, requiring the renewal of the joint packing devices.

In the production of the present invention, the chief objects I have had in view are, first, to provide a piston vane or blade that will effectively hold the motive fluid within the expansion chamber during the period of expansion and prevent leakage of the same; and, second, to provide in a piston vane an improved packing that will not only prevent leakage, but will reduce wear and will automatically take up the latter so as to maintain a steam tight fit notwithstanding such wear as may take place.

With these and other objects in view, which will appear in the following detailed description, the invention consists in the improved structural features hereinafter described in one practical and approved form, and definitely pointed out in the claims hereunto appended.

Referring to the accompanying drawing, wherein I have illustrated an embodiment of the invention which has been found in practice to yield satisfactory results,

Figure 1 is a plan view of the outer edge of the piston vane, that is, the edge which travels in sliding contact with the curved interior wall of the cylinder;

Fig. 2 is a side elevation of the same, broken away and partly in section, and illus-

trating my improved packing strips and their controlling means;

Fig. 3 is a side edge view of the piston vane as seen from the right of Fig. 2;

Figs. 4 and 5 are sectional views, in planes at right angles to each other, through a portion of the engine cylinder, piston drum, driven shaft and bearing boss, illustrating the relation of the piston vane to those parts with which it immediately cooperates.

Referring to the drawing, 10 designates the circular wall of the cylinder, within which is rotatably mounted a drum 11, one end wall of which is keyed to the driven shaft 12, this latter being journaled in a stationary bearing boss 13 integral with one end wall of the cylinder. Mounted at intervals in the cylindrical portion of the drum 11 are rockers or swivel-blocks 14 that are slotted lengthwise to receive the piston blades or vanes 15, which latter are rotatably mounted on the bearing boss 13 through the agency of eccentric straps or bearing rings 16. The features thus far described are broadly common to engines of the general type referred to, and for a detailed description thereof reference may be had to Letters Patent No. 1,320,531 granted to me on the 4th day of November, 1919.

Describing now the novel improvements with which the present invention is concerned, these relate to structural features of the piston vanes or blades, and more particularly the packing features thereof, and are best shown in Figs. 1, 2 and 3. By reference to these views it will be seen that the blade proper 15, which is a flat rectangular member having both a sliding and oscillating engagement with the rocker 14, is formed with longitudinally channeled outer and side edges 16 and 17 respectively. At spaced intervals in the bottom of the outer edge channel 16 are sockets 18 in which are seated coil compression springs 19; and above these springs are slidably mounted in the sockets a corresponding series of pins 20. Within the outer edge channel 16 is mounted with a snug, sliding fit a metal packing strip 21, the lower edge of which rests on the outer ends of the pins 20. Among the novel struc-

tural features of this packing strip 21 may be mentioned, first, longitudinal grooves or channels 22 in its outer edge, whereby the outer or bearing surface of the strip is 5 formed to present comparatively sharp narrow bearing edges 23 which I have found in practice afford a more perfect steam joint than a single bearing surface of the full width of the packing strip. The strip 21 is 10 further provided with a series of relatively small holes 24 extending from the bottom of the grooves 22 through the under side of the strip. These holes, as the outer edge of the vane sweeps across the steam intake port, 15 permit the steam to pass instantly to the under side of the strip, thus balancing the steam pressure on the latter and preventing it from being driven by the steam pressure wholly within the outer edge of the blade 20 itself during its travel across the intake port.

In the bottoms of the side channels 17 are 25 formed similar sockets 25 in which are seated compression springs 26 acting upon pins 27 that in turn thrust outwardly the side edge packing strips 28 that are mounted in the side channels 17 with a snug sliding fit. The meeting ends of the outer packing strip 21 and the side packing strips 28 are lap-jointed as most clearly shown in Fig. 3 at 30 29, and to insure tight joints at the corners the side strips 28 are pressed upwardly by compression springs 30 housed in sockets 31 in their lower ends, the springs 30 seating on pins or lugs 32 that are set into the body 35 portion of the blade at or near the lower or inner ends of the side edge channels 17. These side strips 28 serve to maintain a steam tight fit of the side edges of the piston vane with the web members of the drum 11 40 in the present case, or with the end walls of the cylinder in other types of engines which employ piston blades of this character. It will be observed with reference to Fig. 2 that the outer end channel 16 and the side channels 17 merge into each other behind the outer and side packing strips, as shown by the rounded portions 33 in Fig. 2, whereby steam passing through the holes 24 of the outer strip finds access in rear of the side 45 strips 28 and coöperates with the springs 26 in maintaining the latter in snug contact with the walls engaged thereby.

The packing strips described are preferably 50 of metal, and it will be noted that they are capable of perfect self-adjustment to both the circumferential and side walls which they engage. This result is secured partly by making the side and end strips independent and partly by elastically supporting 55 them at separated points along their length, whereby each end of each strip may move inwardly or outwardly independently of the other end. The provision of means whereby the pressure of steam at the intake port may 60 instantly reach and act upon the inner or

under sides of the packing strips is of great importance in the way of preventing accidental leakage past the outer edges of the packing strips, and constitutes an important feature of the present invention.

70

It will be manifest that the benefits and advantages secured by my invention are not dependent wholly upon the employment of all the detail structural features herein shown and described, and that the latter are 75 capable of modification and variation without involving any departure from the principles involved or sacrificing any of the results and advantages secured. Hence, I do not limit the invention to the specific details 80 shown and described for purposes of illustration, except to the extent clearly indicated in specific claims.

75

I claim:

1. A piston vane having a channeled outer 85 edge and formed with sockets in the bottom wall of said channel, springs seated in said sockets, thrust pins also seated in said sockets and pushed outwardly by said springs, and a packing strip mounted in said channel 90 with its inner edge lying in contact with the outer ends of said pins.

2. A piston vane having a channeled outer 95 edge and formed with sockets in the bottom wall of said channel, springs seated in said 100 sockets, thrust pins also seated in said sockets and pushed outwardly by said springs, and a packing strip mounted in said channel with its inner edge lying in contact with the outer ends of said pins, said packing strip 105 being transversely apertured between its outer and inner edges to admit steam behind the same.

3. A piston vane having a channeled outer 110 edge, in combination with a packing strip 105 mounted in said channel, the outer or bearing edge of said packing strip being longitudinally grooved and said packing strip being provided with one or more apertures extending from the bottom of said groove to the inner edge of the strip to admit steam 115 behind the same, and springs behind said packing strip urging the same outwardly.

4. A piston vane having a channeled outer 115 edge and formed with sockets in the bottom wall of said channel, springs seated in said 120 sockets, thrust pins also seated in said sockets and pushed outwardly by said springs, and a packing strip mounted in said channel, the outer or bearing edge of said packing 125 strip being longitudinally grooved and said packing strip being provided with one or more apertures extending from the bottom of said groove to the inner edge of the strip.

5. A piston vane having channeled outer 125 and side edges, packing strips fitted in said channels respectively and formed with overlapped end portions at the meeting ends of said strips, springs seated in said channels and urging said strips outwardly, and 130

springs acting upon the inner ends of the side strips in the direction of the length of the latter.

6. A piston vane having a channeled outer edge and formed with a plurality of spaced sockets in the bottom wall of said channel, springs seated in said sockets, thrust pins also seated in said sockets and pushed outwardly by said springs, and a metal packing strip fitted in said channel with its inner edge lying in contact with the outer ends of said pins, said packing strip having a series of apertures between its outer and inner edges extending substantially the full length 10 of said packing strip to admit steam behind the same.
7. A piston vane having a channeled outer
- edge and formed with a plurality of spaced sockets in the bottom wall of said channel, springs seated in said sockets, thrust pins 20 also seated in said sockets and pushed outwardly by said springs, and a metal packing strip fitted in said channel and thrust outwardly by said pins, the outer edge of said packing strip being longitudinally grooved 25 to provide a pair of relatively sharp bearing edges, and said packing strip having a series of apertures between the bottom of said groove and its inner edge extending substantially the full length of said packing 30 strip and serving to admit steam behind the same.

JOHN D. CARROLL.
